OXYGEN PURITY IMPROVEMENT METHOD
AND APPARATUS

Samuel C. Collins, Watertown, Mass., Win W. Paget, Michigan City, Ind., and Lewis Tyree, Chicago, Ill., assignors to Joy Manufacturing Company, Pittsburgh, Pa., a corporation of Pennsylvania

Application December 28, 1949, Serial No. 135,462

17 Claims. (Cl. 62—2)

1

Our invention relates to improvements in methods of and means for treating gases. It will be described particularly in its application to production of substantially pure oxygen from air, but this is but illustrative because the process and apparatus disclosed may be used, with appropriate modifications, with various gases to be processed, to produce various particularly desired products which are constituents of the gases to be treated.

For many uses it is important that the purity of the oxygen delivered by an oxygen generator shall be maintained at a high value, as 99.5%. With generators which produce oxygen by the separation of atmospheric air it is at times difficult to maintain this high degree of product purity, and it is important that there shall be provided means for improving the purity when it falls below the required standard. It is also important that such improvement-effecting means be automatically controlled, and highly desirable that it be controlled by the purity of the product itself.

An effective way of improving the product purity, we have discovered, is to deliver to the bottom of the column, when a single column is used, or to an appropriate point when a multiple column is employed, a quantity of the oxygen product. This may be relatively warm oxygen from an outside source, or may be oxygen from any point where a sufficient pressure exists in the generating system, between the point of withdrawal of the oxygen from the column and its point of discharge from the system. When a liquid oxygen pump is used to raise the pressure of the oxygen withdrawn from the column, any point between the pump discharge and the point of final discharge from the system may be selected. The location of the point selected will, however, affect the respective contributions to purity improvement made by the different factors which may play a part.

The rate at which the gaseous oxygen rises in the column markedly affects the purity of the oxygen product, and when relatively warm gaseous oxygen is released to the bottom of the column, speaking here of a single column, the gas rate will be markedly increased. The heat will boil the liquid oxygen more rapidly—increasing the gas flow up the column. In addition the actual volume of gas going up the column will be increased by the returned oxygen.

While it is considered preferable to introduce the warmer oxygen beneath the top of the liquid in the column, its introduction between the liquid level and the bottom of the packing is within the broader aspects of our invention. It is not to be

2

understood that our invention is limited, however, to the introduction of warmer oxygen—oxygen warmer than the temperature at its point of introduction—or to the introduction of oxygen either below the level of liquid oxygen in the column, or at a point below the bottom of the packing. Nor is the invention limited to the production of oxygen.

A point to remember in approaching the invention is that the temperature of the liquid descending through the column is a function of the composition of the liquid, and gets lower as the per cent of oxygen is reduced. In other words, the less pure the liquid passing to the bottom of the column, the colder the liquid which passes to the bottom of the column. This phenomenon we have taken advantage of to provide an automatic control of the rate of oxygen return to the bottom of the column, through the use of the differential between the saturated vapor pressure of a quantity of substantially pure oxygen in a closed system at the temperature at a point at which purity control is desired, and the pressure subsisting in the column at such point. As will later appear, the purity of the oxygen in the automatic control system may be higher or lower than the desired product purity. It will be understood that in the separation of some substances from some mixtures an opposite temperature change takes place with decreasing product purity, and under such conditions use is still made of the differential between the saturated vapor pressure of a quantity, in relatively pure form, of a substance whose purity is to be controlled, at the temperature of a point at which purity control is to be effected, and the pressure at such point in the fractionating apparatus.

It is an object of our invention to provide an improved method of producing oxygen of high purity. It is another object of our invention to provide an improved apparatus for producing oxygen of high purity, having automatic means for insuring the maintenance of the desired high degree of purity. It is a further object of our invention to provide an improved automatic control means for an oxygen generating apparatus for maintaining a high degree of purity of the product thereof. It is still another object of our invention to provide an improved method of treating atmospheric air for the purpose of producing oxygen of high purity and including the step of introducing into the column in which the air is separated into its principal constituents a quantity of liquid oxygen, and desirably of warmer liquid oxygen; and in a preferred embodiment a

warmed portion of the leaving oxygen product, so that by increasing the rate of boiling in the column the rectification process may be improved. It is yet a further object to provide an improved method of regulating an oxygen purity control apparatus. It is still another object of the invention to provide an improved method of improving an end product of a rectification process involving the delivery to an appropriate point in a column of a quantity of warmer gas corresponding generally in constitution to said end product, and automatically controlling the quantity delivered in direct proportion to the deviation of such product from a desired degree of purity. Other objects and advantages of my invention will hereinafter more fully appear.

In the accompanying drawing, in which a single column apparatus embodiment of the invention and a modification are shown for the purpose of illustrating the invention from its apparatus aspect and disclosing the practice of its method aspect,

Fig. 1 is a diagrammatic view of an oxygen generating apparatus having our improved purity control incorporated therein in its illustrative form.

Fig. 2 is a much enlarged view, partially in section and with parts broken away illustrating details of the automatic control apparatus in a preferred form.

Figs. 3 and 4 are further enlarged detail sectional views, respectively on the planes of the section lines 3—3 and 4—4 of Fig. 2, Fig. 4 being partially broken away to a still lower plane, and

Fig. 5 is a view similar to Fig. 2 showing a modified construction.

For the purpose of illustrating our invention we have shown it incorporated in an oxygen generating system which in many respects is closely similar to the system shown in the Samuel C. Collins application Serial No. 383,541, filed October 1, 1953, which is a division of now abandoned application Serial No. 122,077, filed October 18, 1949, for Methods of and Means for Treating Gases. According to that system, air at a temperature of approximately 300° K. and a pressure on the order of 160 p. s. i. (all pressures are gauge unless otherwise indicated) may be delivered from a suitable air compressor (not shown) through a conduit 11 to a valve mechanism generally designated 12, and the effluent (mainly nitrogen) leaving the apparatus may be discharged to the atmosphere or some other desired point through a conduit 13. The valve mechanism 12 is of the mechanically actuated type and is periodically shifted by power, and with a snap action, to reverse the connections of the conduits 11 and 13 with a pair of conduits 15 and 16 which lead from the casing of the valve mechanism 12. Mechanism suitable for this purpose forms the subject matter of an application of Win W. Paget, Serial No. 35,092, filed June 25, 1948, and now Patent 2,638,923. The power for shifting the valve mechanism 12 to effect connection of the air supply conduit 11, now with the conduit 15 and again with the conduit 16, and connection of the conduit 13 with the conduits 16 and 15 while the conduit 11 is connected with the conduits 15 and 16, may be taken from any suitable source, such as the drive shaft of an expansion engine 18, through any suitable reducing gearing. Reversals are adapted to be effected at relatively short intervals; and suitable intervals may be on the order of 3 minutes. Heat exchangers 21 and 22, desirably vertically disposed and formed

as separate units instead of as one longer unit, in order to keep height within desirable limits, are arranged in series, and entering air passes through the heat exchangers 21 and 22 in the order mentioned, while leaving nitrogen passes through these same units in the order 22, 21. Exchanger 21 has three courses, indicated as coaxial courses 21A, 21B and 21C, the first the innermost course and the latter the outermost. The exchanger 22 has similarly relatively arranged courses 22A, 22B and 22C, and, outside the course 22C, a fourth course 22D. Through two of the courses in series in the exchangers 21 and 22, namely courses 21B, 22B and courses 21C, 22C, the entering air and leaving nitrogen flow alternately, the entering air flowing inwardly through one or the other of these pairs of courses and the nitrogen flowing outwardly through the one of such pairs of courses not at any given moment serving for the inflow of the air. Through the third courses 21A of the exchanger 21 and 22A of the exchanger 22, but in the order 22A, 21A, the leaving oxygen product is discharged from the generator. Through the fourth course 22D of the exchanger 22 a portion of the air on its way to the column is caused, after leaving the exchanger 22, to re-circulate through the latter, the better to effect the depositing out of impurities from the entering air stream in the exchanger 22 and their later sublimation and removal from that exchanger, and to increase the temperature of the air entering the expansion engine.

It has been voted with respect to the exchangers 21 and 22, and it will be noted, with respect to further heat exchangers 23 and 24 hereinafter to be described, that the courses are indicated as being coaxial. This is for simplicity of illustration and it will be appreciated that the construction of these heat exchangers may assume various forms. However, exchanger 23 will be observed shortly to be of the four-course type, and exchanger 24 of the three-course type. Subject to these characteristics, it will be understood that a wide range of different constructions may be employed.

Conduit 15 communicates with course 21B of exchanger 21 and conduit 16 with course 21C of exchanger 21, and the leaving oxygen passes outwardly through course 21A of exchanger 21 and passes to a connection S which may lead to a shop line, to a bank of cylinders or to any other desired point or apparatus, for use or storage. Course 21C of exchanger 21 is connected by a conduit 31 with course 22C of exchanger 22. Course 21B of exchanger 21 is connected by a conduit 32 with course 22B of exchanger 22. A conduit 33 connects course 21A of exchanger 21 with course 22A of exchanger 22. These courses are traversed serially in the order 22A, 21A by the oxygen product as later described. It will be understood that air will flow alternately in through course 21C, conduit 31, and course 22C, or course 21B, conduit 32 and course 22B, while concurrently nitrogen will flow outwardly through the ones of said courses and passages last mentioned not carrying the entering air.

A suitable automatic reversing valve mechanism, generally designated 40, is provided at the end of heat exchanger 22 last left by the entering air and first entered by the leaving nitrogen. This includes four automatic check valves 41, 42, 43 and 44. The lower end of course 22B has connected with it a conduit 45 which leads to the check valve 41, and a branch 46 leads from the

conduit 45 to the check valve 42. A conduit 47 leads from course 22C to check valve 44, and a branch 48 connects conduit 47, at a point between course 22C and the check valve 44, with the check valve 43. A conduit 49 connects the other side of check valve 43 with a conduit 50 leading from the check valve 41 to a suitable restrictor device 51 which creates a slight difference between the pressure in the conduit 50 and the pressure beyond the device 51, the latter pressure being on the order of 2 pounds less than the pressure in conduit 50. A conduit 52 connects the conduit 50 with the bottom of course 22D. A conduit 53 leads from the side of check valve 44 opposite the conduit 47 to the outermost course of the heat exchanger 23. Nitrogen always flows outwardly through conduit 53. A conduit 55 connects the side of check valve 42 opposite the conduit 46 to the conduit 53. Each of the check valves 41, 42, 43 and 44 opens in the direction indicated by its $>$ and prevents opposite flow.

The restrictor 51 is connected, as at 56, to a chamber 57 within the top of an evaporator-condenser 60 having a suitably insulated casing 61 and having in said casing an oxygen conducting conduit or course 62 and an air conducting conduit or course 63 in close heat exchange relation with each other. The conduit or course 63 is connected at 54 with the chamber 57. The oxygen conduit or course 62 is connected by a conduit 65 with the bottom of course 22A of exchanger 22. The top of course 22D of exchanger 22 is connected by a conduit 66 with a conduit 67 leading from the chamber 57, and the re-united stream of air passes to a conduit 70 which leads to the expansion engine 18 later more fully described.

When the air entering the system is passing through course 22B it flows past the check valve 41. When course 22B is serving for outflow of nitrogen, the nitrogen flows from conduit 53 through conduit 55 and past check valve 42 and through conduits 46 and 45 to course 22B. When course 22C is serving for inflow of air, entering air flows past the check valve 43. When course 22C is being used to conduct leaving nitrogen, the nitrogen flows past check valve 44 and through conduit 47. As the entering air is at a much higher pressure than the leaving nitrogen, no check valve subjected on its discharge side to air can be opened by the lower nitrogen pressure.

The heat exchangers 23 and 24 have been previously mentioned. The exchanger 23 has four courses: a central one 23A, a next course 23B, a third course 23C, and an outer course 23D surrounding, as shown on the drawings, course 23C. The exchanger 24 has, as shown, a central course 24A, an outer course 24C, and an intermediate course 24B. It will of course be understood that the several courses are in good heat exchange relation with respect to each other.

The connection of conduit 53 is with the top of the outermost course 23D of exchanger 23. The bottom of course 23D is connected by a conduit 68 with the bottom of course 24C of exchanger 24, and the top of course 24C is connected by a conduit 71 with a nitrogen outlet (the efflux connection) 72 of a single column 73. The internal construction of this column and certain special adjuncts associated with it will be described after the general system has been considered as a whole. The compressed air course 63 of the evaporator-condenser 60 is connected by a conduit 74 with the top of course 75

23B of exchanger 23. The bottom of this last course is connected by a conduit 75 with a valve device 76 which, in the particular apparatus shown, and when the latter is used for oxygen production, is adjusted to effect a pressure drop between its opposite sides on the order of 88 p. s. i. for a compressor delivery pressure of 160 p. s. i. This is substantially the same reduction in pressure as occurs in the expansion engine 18 later described, when the latter is operating with its longer period of admission hereafter more fully explained. The downstream side of valve device 76 is connected with a conduit 77 which leads to a condenser coil or element 78 in the lower end of the column 73. The central course 23A of exchanger 23 is connected at its top with a conduit 79 leading to the oxygen course 62 of the evaporator-condenser 60, while the bottom of the course 23A is connected with the bottom of the central course 24A of exchanger 24 by a conduit 80. A conduit 81 leads from the top of the central course 24A and is connected with the discharge of a liquid oxygen pump later described. The condenser unit 78 is connected at its other end (from the conduit 77) by a conduit 82 with the intermediate course 24B of exchanger 24. The top of course 24B is connected with a conduit 83, of which more will shortly be said.

The remaining course 23C of exchanger 23 is connected at its top with an expanded air conduit 85, and its lower end is connected by a conduit 86 with a check valve 87 openable towards the conduit 77 and connected with the latter by a connection 88. The check valve 87 opens toward the conduit 77, but only when the pressure in the conduit 86 is sufficient to effect opening of check valve 87 against the pressure in conduit 77.

The expansion engine 18, which may be of the construction shown in the co-pending Samuel C. Collins application Serial No. 665,206, filed April 26, 1946, and now Patent No. 2,607,322 provided with suitable means for predeterminedly lengthening and shortening the period of admission, or which may be of the character of the expansion engine employing cam follower rollers one or both of which coat with a cam depending on whether early or late cut-off is desired, which expansion engine is illustrated and described in an application of Win W. Paget, Serial No. 31,017, filed June 4, 1948, now Patent No. 2,638,923, May 19, 1953, or of other suitable construction, includes a cylinder 90 having admission and exhaust valves, not shown, and to the admission valve of which air under pressure is admitted from the conduit 79 through a conduit 91 with which an "In" surge tank 92 is connected so as to minimize fluctuations in flow. A discharge or exhaust connection 93 leads from the expansion engine to a "Discharge" surge tank 94 which may have associated with it a strainer to catch any snow which might otherwise attain to the column while the heat exchangers 23 and 24 were not fully cooled down during the starting of the apparatus. The expansion engine supports on the top of its cylinder a jacketed liquid oxygen pump 95 of any suitable construction, the liquid oxygen pump being, for example, actuated by the expansion engine piston, as is the pump shown in the last above mentioned application of Win W. Paget, or in any other suitable manner. The conduit 81 is connected with the discharge of the liquid oxygen pump 95 while this pump has a suction connection 96 leading to it from a strainer 97 which is cooled or jacketed by liquid air, the jacket herein being represented

by a coil 98. To the strainer 97 a conduit 100 leads from the evaporator-condenser at the bottom of the column 73, the conduit 100 communicating with the condenser-unit-enclosing chamber 101 in the bottom of the column at a point at the desired liquid oxygen level in the latter.

The "Discharge" surge chamber 94 has connected with it a conduit 105 which is connected to a valve structure 106, which valve structure includes a passage or chamber 107 continuously in communication with the conduit 85 and another chamber 107' connected through a conduit 109 with the interior of the column at a point spaced an appropriate distance from the top of the latter. The valve structure 106, which may be called a by-pass valve is adapted to have the two chambers mentioned connected in communication with each other and thus to connect the "Discharge" surge chamber 94 in free communication with the upper part of the column through the conduit 105, valve structure 106 and conduit 109. In the drawing, the constant communication between the conduits 105 and 85 is indicated by the passage or chamber 107, and the communicability of the passage or chamber 107 with the conduit 109 is indicated by the valve 108. Details of valve 106 can be better understood by reference to Patent 2,588,656 to Win W. Paget.

The expansion engine 18 is provided with valve gear adapted to permit the engine to operate with admission for a relatively short portion of its working stroke or with admission for a considerably larger portion of its working stroke. When cutoff is relatively late in the working stroke, the valve structure 106 will prevent communication between the "Discharge" surge chamber 94 and the column through the conduit 109; and when communication between the "Discharge" surge chamber 94 and the column is effected by the appropriate adjustment of the valve structure 106, the expansion engine will be operated with admission for said relatively short portion of its working stroke. Various means may be provided for effecting the desired changes in period of admission of the expansion engine, as for example, with a cam-opened admission valve as shown in the Samuel C. Collins Patent No. 2,607,322, the provision of selectively operable cams with different dwells, or cams one relatively adjustable with respect to the other, or cam follower rollers one or both cooperating with the cam depending upon whether early or later cutoff is desired, may be employed, as in the apparatus of the Paget expansion engine application.

Only such air will flow through the evaporator-condenser 60 as cannot pass through the expansion engine. When the latter is operating with relatively late cutoff, complete condensation of the fraction of the entering air which passes through the air course 63 of the evaporator-condenser 60 may conceivably be effected, but if more air passes through this course than can be condensed by the available cold provided by evaporation of liquid oxygen in the course 62 of the evaporator-condenser 60, at the pressure (on the order of 50 p. s. i.) which then exists in that course, the excess unliquefied air will be 70 condensed in evaporator-condenser 78.

The conduit 83, previously mentioned, leads to a valve device 110 which is adapted to be adjusted to effect a reduction on the order of 60 p. s. i. in the pressure of the fluid (liquid air) 75

which flows through it; and the downstream side of the valve device 110 is connected by a conduit 111 with the jacket 98 for the strainer 97; and the top of this jacket is connected by a conduit 112 with a jacket 113 of the liquid oxygen pump 95, there being a conduit 114 leading from the jacket 113 to a connection 115 through which liquid air may be admitted to the top of the column 73.

The column 73 may be of any suitable construction, and is illustrated as of the conventional packed type. Of whatever type it may be, it will provide a large cumulative surface area at which a rising current of a gas and a descending stream of liquid may interact.

The column may normally be operated with a pressure on the order of 6 or 7 p. s. i., and in order to evaporate liquid oxygen with the latent heat of condensation of air under pressure in the condenser 78, the pressure of the air in said condenser should be on the order of 70 p. s. i., and accordingly the valve 110 will be set to maintain a differential in pressure of about 60 p. s. i. between its upstream and downstream sides, the downstream side being substantially at column pressure, and the upstream side substantially at a pressure of 70 p. s. i. The expansion engine, when working with the later cutoff, has an expansion through it at least substantially equal to the difference between 158 p. s. i., the pressure in line 70, and the pressure in the line 77. Thus the expansion engine provides a pressure drop on the order of 88 p. s. i. This 88 p. s. i. drop, plus the 70 p. s. i. pressure previously mentioned, plus the differential in pressure of about 2 p. s. i. provided by the resistor 51, gives a cumulative pressure of 160 p. s. i.; and that is the pressure at which the two-stage compressor, not shown, which delivers air to the conduit 11, 40 may deliver air continuously. It is to be noted that the conduit 75 and valve device 76 are substantially in parallel with the expansion engine and the check valve 87, and accordingly the valve device 76 is set to give a pressure reduction on the order of 88 p. s. i., so that the air starting at 158 p. s. i. in the chamber 57 and passing through the air course 63, conduit 74, and past valve device 76 may attain to the pipe 77 at 45 substantially the pressure at which the air is delivered through the conduit 88. Thus, it may be observed that the sum of the column pressure, plus the reduction in pressure at the valve device 110, plus the pressure reduction across the valve device 76, plus the 2 p. s. i. drop through the resistor 51 and plus the resistance in various conduits also equals 160 p. s. i., the delivery pressure of the compressor supplying compressed air to the conduit 11.

60 The apparatus, we may call it a generator, may be operated to provide oxygen at relatively low pressures, say on the order of 50 p. s. i. and at relatively high pressures, say on the order of 2000 p. s. i.

65 Regardless of which system of operation may be in use, liquid oxygen drawn from the chamber 101 in the column 73 through conduit 100, the strainer 97, and conduit 96, is pumped by the liquid oxygen pump 95 through the conduit 81, through the course 24A of heat exchanger 24, through the conduit 80, the course 23A of heat exchanger 23, conduit 79, the oxygen course 62 of the evaporator-condenser 60, the conduit 65, course 22A of heat exchanger 22, conduit 33, and the course 21A of the heat exchanger

21, and finally is delivered at the desired terminal pressure through the product delivery pipe S. And the nitrogen leaving the column by way of the connection 72 passes through the conduit 71, through course 24C of heat exchanger 24, through conduit 68, through course 23D of heat exchanger 23, through conduit 53, through one or the other of the courses 22B or 22C of heat exchanger 22, through one or the other of the conduits 31 or 32, through one or the other of the courses 21B or 21C of heat exchanger 21, through one or the other of the conduits 45 or 46, and through the escape 43, having passed through appropriate passage means in the valve mechanism 42. Thus it will be evident that the streams of oxygen and nitrogen passing through the heat exchangers 22 and 21 will cause carbon dioxide and water vapor in the entering air stream, supplied perhaps at 300° K. and 150 p. s. i., to be condensed, or condensed and frozen, on the walls of the passages in these exchangers through which the entering air may at any given moment be flowing, and that liquid water will be evaporated or entrained, and deposits of ice and carbon dioxide snow sublimed, and be carried out, by the leaving nitrogen stream, of the passages in which they have been deposited. A portion of the air which is passed through the heat exchangers 21 and 22 is caused to pass again through the heat exchanger 22, through a course 22D thereof, as previously explained, flowing through the conduit 52, course 22D, and conduit 66 and rejoining the main mass of air which passes, during the production of low pressure oxygen, through the chamber 57 and conduit 67; and the reunited streams pass through the conduit 70 and the conduit 91 into the expansion engine to be expanded therein and to be cooled by the performance of work during the adiabatic expansion of the fluid in the expansion engine. The flow through conduit 52, course 22D of heat exchanger 22, and conduit 66 is caused by the device 51, which provides approximately a 2-pound difference in pressure at its opposite sides.

During the production of oxygen at 50 p. s. i., about 12% of the total mass of entering air passes through the air course 63 of evaporator-condenser 60 in heat exchange relation with the leaving oxygen product. When oxygen at 2000 p. s. i. is the desired product, as much as 60% of all the air may pass through the air course 63 of evaporator-condenser 60. The air which leaves the heat exchanger 22 on its way to pass through the chamber 57 of evaporator-condenser 60 and flow through the conduit 67 is at a temperature of 115° K. and a pressure of 160 p. s. i. gauge. At the downstream side of the restrictor device 51 the pressure is 158 p. s. i. gauge. The recirculated air which flows through the conduit 66 is at a pressure of on the order of 158 p. s. i. and a temperature of 180° K. just before it joins the fluid stream in conduit 67. When the streams have been mingled in the conduit 70, all the air is at a temperature of 135° K. and a pressure of 158 p. s. i. The portion of the air which flows through the conduit 70 and does work in the expansion engine leaves the latter at a temperature of 110° K. and a pressure of 70 p. s. i. when 50-pound oxygen is to be produced. This expanded air passes through the conduit 85, through course 23C of heat exchanger 23, and emerges at a temperature of 105° K. and a pressure of 70 p. s. i. gauge, and passes the check valve 77 to mix with liquid air which has passed

the valve device 76, and there is formed a stream partially of liquid air and partially of expanded air at a temperature of 100° K. and a pressure of 70 p. s. i. The air from the air course 63 of the evaporator-condenser 60 emerges from heat exchanger 23 and enters the conduit 75 at a temperature of 112° K. and a pressure of 158 p. s. i. After passing through the valve device 76 and undergoing a drop in pressure of about 88 p. s. i., the liquid air is at the same pressure as the expanded air coming through conduit 86. The mixture of liquid air and expanded air at a temperature of 100° K. and a pressure of 70 p. s. i. enters the condenser coil 78 and is condensed by reason of the giving up of heat in the process of vaporizing oxygen in the bottom of the column. The liquid air emerging from the condenser 78 is at a temperature of 96° K. and a pressure of 70 p. s. i., and after this liquid air has passed the valve device 79 and had its pressure reduced by approximately 60 p. s. i., the liquid air will be at a temperature of 83° K. and a pressure of about 9 p. s. i., having in mind friction losses in the passages. Following the jacketing of the oxygen strainer 97 and the liquid oxygen pump 95, the still liquid air will enter the top of the column at a temperature of 83° K. and a pressure of perhaps 7 p. s. i., taking into consideration friction losses, and it will be rectified in the column so that substantially pure oxygen (99.5% pure, at least) can be drawn from an appropriate point in the evaporator-condenser arranged in the bottom of the column at a temperature of 95° K. and a pressure of 7 p. s. i. This liquid oxygen will flow through the strainer 97, conduit 96, the liquid oxygen pump 95, the conduit 81, and the central courses, in series, of heat exchanger 24, heat exchanger 23, evaporator-condenser 60, heat exchanger 22, and heat exchanger 21, and emerge, when 50-pound oxygen is being produced, in the form of gaseous oxygen at the mouth of the product pipe S.

When oxygen at relatively high pressure, say at a pressure suited for cylinder charging, is to be produced, the valve structure 106 will be operated to connect the conduits 105 and 109 and the expanded air leaving the expansion engine will then pass through the conduit 105, the valve structure 106, and the conduit 109 into the column, and the pressure of the air in the conduit 105 will be reduced substantially to that within the column, and accordingly no more expanded air will be discharged through the check valve 87, because this valve will be held closed by the pressure, on the order of 70 p. s. i., which subsists in the conduit 77. At the time the valve structure 106 is operated to permit the exhaust from the expansion engine to pass substantially directly into the column through the conduit 109, the point of cutoff of the expansion engine 108 will be changed to make it much earlier in the stroke; and, the speed of the expansion engine remaining unaltered, much less—roughly half as much air can go through the expansion engine. As a result of this, the air which cannot flow through the conduit 77 and be passed through the expansion engine will of necessity go through the air course 63 of evaporator-condenser 60, and, having passed through course 23B of heat exchanger 23, this now much larger mass of air, perhaps 60% of the total mass, will pass through the valve device 76 and enter the condenser coil 78 of the evaporator-condenser at

the bottom of the column 73 and be liquefied therein. This larger volume could not be liquefied in the evaporator-condenser 60 and the heat exchanger 23 because the oxygen now at a much higher pressure cannot be vaporized at the temperature of condensing air. The reduced volume of liquid air from condenser coil 78 will pass through the heat exchanger 24 by way of course 24B and next pass through conduit 83 and the valve device 110 and then, after jacketing the strainer 97 and the liquid oxygen pump 95, will be passed into the top of the column for rectification. A much smaller percentage of the total oxygen content of the air entering the apparatus will be delivered during the production of 2000-pound oxygen than during the production of 50-pound oxygen.

The foregoing description of the modes of operation of the generator are probably more than adequate as a basis for an understanding of our invention which will now be described, but should further details be desired they will be available in the patent to be issued upon the application of the applicant Collins, Serial No. 383,541, hereinabove referred to.

As previously indicated, we have found that the quality of the oxygen product may be substantially improved, when necessary, by returning a portion of the product to the bottom of the column. For this purpose we have provided, according to the illustrative embodiments of the invention in its apparatus aspect arrangements as follows:

The column is provided with a tapered perforated element or screen C of conical shape arranged at the bottom of its packed space and disposed with the apex of the cone downward. The product line S has a branch 115 equipped with a pressure reducing valve 116 adapted to maintain at its output side a predetermined pressure. A pressure on the order of five pounds above column pressure is suitable. This pressure reducing valve delivers relatively warm gaseous oxygen to a conduit 117, which leads to a valve mechanism generally designated 118. Two possible forms of such a valve mechanism are illustrated, the preferred form shown in Figs. 1 and 2. The valve mechanism 118 (or 118') is adapted to effect, when this is desirable, connection of the conduit 117 with a conduit 119 opening at 120 through the bottom of the column beneath the level of the liquid oxygen therein. It is desirable to control the introduction of oxygen to the bottom of the column automatically in accordance with the purity of the product being formed.

Secured to the inverted cone C, as by legs 123, herein shown as four in number, is a dish-like element 125 to which there is connected a nearly annular bulb 126. In this bulb there is a quantity of a liquid the variations in the saturated vapor pressures of which are to be used to effect the desired automatic control. In the case of oxygen production, the bulb may be filled either with at least substantially pure liquid oxygen and its saturated vapor or may contain in liquid and saturated vapor form a quantity of oxygen of somewhat less purity than the purity of the desired oxygen product. In both cases it will be noted that the bulb contains a substance relatively close in constitution to the constitution of the desired product. The bulb 126 is connected by a tube 128 with a passage 129 in the valve mechanism 118, as at 130. Further details of this passage 129 and its relation to the valve mechanism will be later given. Another conduit

131, having an open mouth 132 within the column just below the bulb 126 is connected also with the valve mechanism 118 at 133. The open end 132 is downwardly directed as at 134 in order that liquid oxygen may not, as would perhaps be the case were it inverted from the position shown, tend to enter the mouth of the tube 131 and flow into the valve mechanism 118.

The valve mechanism 118 (as does also the simpler valve mechanism 118' of Fig. 5) includes a casing 135 provided with a bellows chamber 136, and a bore 137 formed in the upper part of the casing 135 opens at its lower end into the chamber 136 and is arranged coaxially with the chamber. Within the bore 137 there is mounted a valve block 138 which has threads 139 at its upper end engaging with threads 140 formed in a projecting neck-like portion 142 on the casing 135. A head 143 is provided on the valve block 138 for permitting adjustment of the latter in the bore 137.

The valve block 138 is provided with a plurality of grooves in its periphery. These include relatively remote grooves 145 and 146 whose primary function is that of improving sealing. To that end they contain O rings O. There are other spaced grooves 148 and 149 formed in the valve block, these, like the first grooves, being annular grooves, and being disposed between the grooves 145 and 146. Between the grooves 148 and 149 is another sealing groove 150 also provided with an O ring O. The grooves 148 and 149 communicate with each other through the formation in the valve block of diametrically extending passages 151 and 152, connected with each other by an axial passage 154. The passage 151 at its opposite ends opens into the groove 148, and the passage 152, at its opposite ends, opens into the groove 149. The axial passage 154 has an enlargement 155 at its lower end, and communicates at its upper end with the diametric passage 151, and at its lower end with the diametric passage 152, through the enlargement 155. A "needle"-type valve element 157, having a conical end 158 adapted to cooperate with a circular seat 159 formed at the upper end of the enlargement 155, may seal off communication between the grooves 148 and 149, or permit variable communication between them. It may be noted, before describing control means for the valve 157, that the groove 148 is connectable, in the preferred embodiment of Fig. 2, by a further control valve mechanism 160, which will shortly be described in detail, and a passage 161 with the conduit 117 (in Fig. 5 the connection is direct). The groove 149 is connected by a passage 162 with the conduit 119. Accordingly, when the valve element 157 moves downwardly there may be communication between the conduit 117 and the bottom of the column. In the embodiment of Fig. 2 an auxiliary communication will be effected which may much exceed in flow capacity the communication possible with the structure shown in Fig. 5.

65 The control for the valve 157 may now be noted.

Within the chamber 136 there is arranged a bellows device 164. A so-called plug 165 is adapted to be suitably secured as by rivets 166 to a radially extending flange 167 formed on the lower end of the casing 135, a suitable spacer ring 168 being provided properly to locate the upper end of the plug 165. The plug is traversed by two longitudinally extending passages: the 75 passage 129, previously mentioned, and a parallel

passage 169 normally closed by a plug 170. At their upper ends the passages 129 and 169 communicate with a diametric passageway 171 opening into an annular groove 172 formed in the periphery of a reduced upwardly extending portion 173 of the plug member 165. Surrounding this reduced portion 173 is a sleeve member 175, having a radial portion 176 at its lower end carrying integrally with it a threaded ring portion 177, which engages threads 178 on the plug member 165. The bellows device 164 is appropriately secured in fluid tight relation, as at 180, to the radial portion 176 associated with the sleeve member 175. The top of the bellows 164 is suitably secured, as at 182, in fluid tight relation to an annular member 183, to which there is secured a central valve supporting element 184 having an upwardly extending hollow sleeve-like portion 185, within the bore 186 of which the lower end of the valve element 157 is received with slight clearance. The lower end of the valve element is rounded as at 157B. The sleeve-like portion 185 is surrounded by a groove 190, in which a discontinuous resilient wire ring 191 is seated; and this ring has a radially inwardly extending, transverse arm portion 192, which enters a transverse bore 193 in the valve 157 and engages the wall of this bore about at the axis of the valve, and which is adapted, through the flexure of the radial arm portion 192, to press the valve 157 against the bottom of the bore 186, but to permit a slight uncentering of the valve relative to the bellows 164, thereby avoiding cramping. The connection 133 opens through a conduit 195 into the chamber 136. As the connections of the bellows device 164, at 180 and 182, are fluid tight, as above noted, it will be appreciated from the arrangements described that the exterior of the bellows is subjected to the pressure at the mouth 132 of the conduit 131, while the interior of the bellows is subjected to a pressure which varies with the temperature of the fluid contained in the chamber of the bulb 126.

The control apparatus so far described is common, with the exception noted, to the embodiments of Figs. 2 and 5. It is all that the embodiment of Fig. 5 includes and all that is required for operativeness, but for the admission of larger amounts of oxygen back into the bottom of the column, the control 160 previously referred to is desirable. Referring, therefore, to Fig. 2, the construction and arrangement of this control are as follows:

A housing or casing 200 is provided in association with the casing 135. It is hollow and contains a diaphragm 201 forming at the opposite sides thereof chambers 202 and 203. A small passage 204 in the diaphragm connects the chambers 202 and 203. A suitable connecting member 205 connects the housing 200 with the valve mechanism 148. A passage 206 in the connecting member 205 connects the chamber 203 with the passage 161. A spring 207 normally maintains the diaphragm against a seat 208. The diaphragm has a plate 208V secured to it which acts as a valve in cooperation with the seat 208. A passage 209 leads from the seat to a conduit 210 which connects with the conduit 119 as by a T connection 211. The conduit 117 is connected with a passage 212 which opens into the chamber 202.

In the embodiments of both Figs. 2 and 5, when the bellows 164 moves the valve 157 from its seat, oxygen product flows from the conduit 117 to the conduit 119. This flow, in the embodiment of Fig. 5, is directly regulated by the needle valve 157. In the embodiment of Fig. 2, the needle valve 157 controls some (a very slight) oxygen flow itself, and also plays a pilot function

5 for the valve plate 208V and its supporting diaphragm. Substantially opening of the valve 157 causes a pressure drop in the chamber 203 as the passage 204 is too small to deliver as much oxygen as the open valve 157 can permit to pass it. The 10 then greater pressure in the chamber 202 will therefore move the diaphragm 201 against the tension of the spring 207, moving the valve 208V away from the seat 208, and allow oxygen product to flow directly from the conduit 117 through 15 the chamber 202, passage 209 and the conduit 210 to the conduit 119 which opens into the bottom of the column beneath the level of the liquid oxygen therein.

It will be understood that, if the substance in 20 the bulb 126 is oxygen of greater purity than the oxygen product sought for, the vapor pressure under the bellows 164 will be slightly below the pressure in the column at 132 when the liquid flowing over the bulb is of the desired purity, 25 while, if the substance in the bulb 126 is oxygen of less purity than the oxygen product sought for, the vapor pressure within the bellows 164 will be slightly greater than the pressure within the column at 132 when the liquid flowing over the bulb is of the desired purity. Accordingly, the element 138 will be adjusted in the first case further inward than in the second case, because in the first case the bellows will be slightly axially shorter than in the second when the valve 157 30 is just held against its seat with sufficient pressure to resist the pressure of the oxygen in passage 154. In both cases, however, when the temperature of the liquid flowing over the bulb 126 is reduced, as occurs when its purity falls below 35 desired product purity, the pressure within the bellows 164 will be so reduced as to effect oxygen admission to the column because the pressure within the conduit 131 and outside of the bellows 164 does not vary materially as the pressure within 40 in the bulb 126 does. Thus a decrease in the purity of the oxygen in the bottom of the column is as it were anticipated, and the valve 157 is moved from its seat and, in the embodiment of Fig. 5, allows oxygen product to flow through 45 the conduit 117, the groove 148, the diametric passage 151, the axial passage 154, the enlargement 155, the diametric passage 152, the annular groove 149, the passage 162 and the conduit 119 into the liquid oxygen in the bottom of the column, entering the latter at 120, as previously 50 noted the pressure reducing valve 116 being set so as to provide a pressure in the conduit 117 just slightly exceeding the sum of the desired column pressure and the head of the liquid oxygen. 55

With the construction illustrated in Fig. 2 downward movement of the valve 157 from its seat results, as previously noted, in the provision of an opportunity for oxygen to flow from the chamber 203 through the passages 206, 161, 151, 154, 152 and 162, and the conduit 119, into the bottom of the column. The flow capacity will normally quickly exceed the potential rate of flow of oxygen from the chamber 202 through the restricted passage 204 to the chamber 203. Thus the pressure at the left-hand side of the diaphragm 201 would be less than exists at the right-hand of this diaphragm and the valve plate 208V will be raised from the seat 208, thus permitting the flow of a substantial quantity of relatively warm oxygen from the conduit 117 through 60 65 70 75

the passage 212, the chamber 202, the passage 209, the conduit 210 and the conduit 119 into the bottom of the column. This arrangement provides for a greater range of control of oxygen purity. When the oxygen dripping into the dish-like element 125 improves in percentage of purity the temperature will increase and this will be attended by increase in the pressure inside the bellows 164 and the closing of the valve 157. In the form of the invention illustrated in Fig. 5 this will directly reduce or entirely shut off, as the case may be, the flow of oxygen to the bottom of the column and, in the form of Fig. 2 it will result in an appropriate control of the position of the diaphragm 201 and the valve plate 203V and the resultant control of the volume of oxygen passing into the bottom of the column.

It will be clear that the quantity of oxygen product admitted to the bottom of the column may vary from none at all to a substantial amount, depending on the operating conditions, and the quantity will be regulated and controlled automatically by the mechanism which has been described.

It will be observed that we have provided an improved method and two improved physical embodiments of apparatus for improving and automatically controlling the purity of the oxygen produced by a generator. The improvement effected is a definite one and it may be accomplished without the necessity for frequent intervention of an attendant.

It will be understood that our invention is not limited to the improvement of oxygen purity, but with suitable adaptation and with the substitution in the bulb of a quantity in substantially pure form of the product whose purity is to be controlled, it may be used in other rectification processes. By "substantially pure form" we intend to include not only substantially chemically pure substances, but to cover broadly the concept of substantial identity in constitution with the product desired, even though the latter itself be a mixture. "Substantially pure form" is also intended to cover not only a condition of slightly greater purity than the purity of product desired, but also a condition of slightly lower purity than that desired for the product. Moreover, it is not limited in its broader aspects to introduction of the warmer vapor below the level of the liquid product in the column or even to the introduction of a vapor at a higher temperature than subsists at its point of introduction.

While there are in this application specifically described two physical embodiments which the invention may assume in practice from its apparatus aspect and by which its method aspect may be practiced, it will be understood that these are disclosed for purposes of illustration and that the invention may be modified and embodied and practiced in various other forms and ways without departing from its spirit or the scope of the appended claims.

What we claim as new and desire to secure by Letters Patent is:

1. The method of maintaining the purity of a product of rectification in a column, which includes withdrawing the product in a liquid state from the column, mechanically increasing the pressure of the withdrawn product while in the liquid state, vaporizing and warming the withdrawn product through heat exchange with a mixture of which the product is one component, which mixture is on the way to the column for rectification therein, and the return to a point

in the column below the liquid level of such product in the column of a quantity of such product in its gaseous state and at an at least slightly higher pressure than the pressure in said column at such point of return.

2. The method of maintaining the purity of a product of rectification in a packed column which includes the return to a point in the column below the liquid level of such product in the column of a quantity of such product having a higher heat content per unit of mass than does said product in the column and at an at least slightly higher pressure than the pressure in said column at such point of return and the control of the quantity of such product so returned by the temperature of the product in liquid state at the completion of its passage through the column packing and above the liquid level of such product in the column.

3. The method of improving the purity of a product of rectification in a packed column which includes the return to a point in the column below the liquid level of such product in the column of a quantity of such product in its gaseous state and at an at least slightly higher pressure than the pressure in said column at such point of return and the control of the quantity of such product so returned by the temperature of the product in liquid state at the completion of its passage through the column packing and above the liquid level of such product in the column.

4. The method of maintaining the purity of a product of rectification in a column, which includes withdrawing the product in a liquid state from the column, mechanically increasing the pressure of the withdrawn product while in the liquid state, vaporizing and warming the withdrawn product through heat exchange with a mixture of which the product is one component, which mixture is on the way to the column for rectification therein, and the delivery to a point in the column, below the liquid level of such product in the column, of a quantity of such product at a higher temperature and at an at least slightly higher pressure than the pressure in said column at the point of introduction of such product into the column.

5. The method of maintaining the purity of a product of rectification in a column, which includes withdrawing the product in a liquid state from the column, mechanically increasing the pressure of the withdrawn product while in the liquid state, vaporizing and warming the withdrawn product through heat exchange with a mixture of which the product is one component, which mixture is on the way to the column for rectification therein, and the delivery to a point in the column, below the liquid level of such product in the column, of a quantity of such product in the gaseous state and at a higher temperature and at an at least slightly higher pressure than the pressure in said column at the point of introduction of such product into the column.

6. A method of producing oxygen of a preselected purity including compressing, cooling and liquefying air and rectifying it in a column at a relatively low temperature and reduced pressure thereby producing a liquid oxygen product and a nitrogen-rich effluent, and when the temperature of the oxygen reflux is reduced due to a falling off in purity of such reflux, utilizing such reduction in temperature applied as a control at a point above the liquid oxygen product level to

effect a return of a controlled quantity of oxygen product to the bottom of the column.

7. In a procedure in which a stream of relatively pure oxygen in liquid form is withdrawn, following an air fractionating operation, from a liquid pool in a rectifying column, has a pressure mechanically imposed upon it, and is vaporized and warmed through heat exchange with a stream of air en route to separation, the steps for raising the purity of the oxygen product when it falls below a desired value which include withdrawing oxygen vapor so warmed from a stream of oxygen product, and delivering, under the control of the temperature of the oxygen product in liquid form in the rectifying column before it enters such pool, variable quantities of the warmed oxygen vapor to such a liquid pool below the surface thereof.

8. In a procedure in which a stream of relatively pure oxygen in liquid form is withdrawn, following an air fractionating operation, from a liquid pool in a rectifying column, has an increase in pressure mechanically imposed upon it, and is vaporized through heat exchange with a stream of air en route to separation, the steps for raising the purity of the oxygen product when it falls below a desired value which include withdrawing oxygen vapor from a stream of oxygen product, delivering variable quantities of the warmed oxygen vapor to such a liquid pool below the surface thereof and controlling the quantity of oxygen product so delivered by the variations in the purity of the oxygen reflux above such pool.

9. In combination, in a gas separation apparatus, a column containing means for providing a large cumulative surface area at which a rising current of a gas and a descending stream of liquid may interact, and having below the lowest part of such means a collecting space for a liquid, relatively pure product of the rectification process performed within said column, means for withdrawing such relatively pure product from said collecting space, means for vaporizing the same and for making the same available in the gaseous state at a pressure exceeding the pressure within said column and at a temperature higher than the temperature of said product in said collecting space, means for conducting some of said product into said collecting space at a point therein below the top of the liquid standing therein, and means for controlling the quantity of said product conducted into said collecting space including a valve having controlling means responsive to the temperature of the descending stream of liquid as it reaches the bottom of said first mentioned means.

10. In combination, in a gas separation apparatus, a column containing means for providing a large cumulative surface area at which a rising current of a gas and a descending stream of liquid may interact, and having below the lowest part of such means a collecting space for a liquid, relatively pure product of the rectification process performed within said column, means for withdrawing such relatively pure product from said collecting space, means for vaporizing the same and for making the same available in the gaseous state at a pressure exceeding the pressure within said column and at a temperature higher than the temperature of said product in said collecting space, means for conducting some of said product into said collecting space at a point therein below the top of the liquid standing therein, and means for controlling the quantity of said product conducted into said collecting space including a valve

having controlling means responsive to the temperature of the descending stream of liquid as it reaches the bottom of said first mentioned means and including a bellows device and means for subjecting the latter on its opposite sides to the pressure above the liquid in said collecting space and to the vapor pressure of the pure product at the temperature of said descending stream of liquid at the point stated.

- 10 11. In combination, in an air separation apparatus, a column containing means for providing a large cumulative surface area at which a rising current of a gas and a descending stream of liquid may interact, and having below the lowest part of such means a collecting space for relatively pure liquid oxygen, means for withdrawing such relatively pure liquid oxygen from said collecting space, means for vaporizing the same and for making the same available in the gaseous state at a pressure exceeding the pressure within said column and at a temperature higher than the temperature of said liquid oxygen in said collecting space, and means for improving the purity of said relatively pure liquid oxygen including means for supplying not less pure and warmer gaseous oxygen into said collecting space at a point therein below the top of the liquid standing therein, and means for controlling the quantity of said gaseous oxygen conducted into said collecting space including a valve having controlling means including an oxygen filled bulb disposed in said collecting space above the liquid level therein and responsive to the temperature of the descending stream of liquid as it reaches the bottom of said first mentioned means.
- 20 12. In combination, in an air separation apparatus, a column containing means for providing a large cumulative surface area at which a rising current of a gas and a descending stream of liquid may interact, and having below the lowest part of such means a collecting space for relatively pure liquid oxygen, means for withdrawing such relatively pure liquid oxygen from said collecting space, means for vaporizing the same and for making the same available in the gaseous state at a pressure exceeding the pressure within said column and at a temperature higher than the temperature of said liquid oxygen in said collecting space, and means for improving the purity of said relatively pure liquid oxygen including means for supplying not less pure and warmer gaseous oxygen into said collecting space at a point therein below the top of the liquid standing therein, and means for controlling the quantity of said gaseous oxygen conducted into said collecting space including a valve having controlling means including an oxygen filled bulb disposed in said collecting space above the liquid level therein, and means for effecting the flow over the same of the descending stream of liquid as it reaches the bottom of said first mentioned means.
- 30 13. In an air separation apparatus which includes a column containing means for providing a large cumulative surface area at which a rising current of a gas and a descending stream of liquid may interact, and having below the lowest part of such means a collecting space for relatively pure liquid oxygen, and means for effecting delivery for use of such relatively pure oxygen from said collecting space, means for improving the purity of the oxygen product including means for introducing oxygen in gaseous form into said collecting space at a point therein below the top of the liquid oxygen therein and means for regulating the quantity of oxygen introduced includ-

ing a control valve and controlling means therefor governed by the temperature of the descending stream of liquid as it reaches said collecting space.

14. In an air separation apparatus which includes a column containing means for providing a large cumulative surface area at which a rising current of a gas and a descending stream of liquid may interact, and having below the lowest part of such means a collecting space for relatively pure liquid oxygen, and means for effecting delivery for use of such relatively pure oxygen from said collecting space, means for improving the purity of the oxygen product including means for introducing oxygen in gaseous form and at a higher temperature than said relatively pure oxygen in said collecting space into said collecting space at a point therein below the top of the liquid oxygen therein and means for regulating the quantity of oxygen introduced including a control valve and controlling means therefor including a further valve governed by the temperature of the descending stream of liquid as it reaches said collecting space.

15. In an air separation apparatus which includes a column containing means for providing a large cumulative surface area at which a rising current of a gas and a descending stream of liquid may interact, and having below the lowest part of such means a collecting space for relatively pure liquid oxygen, and means for effecting delivery for use of such relatively pure oxygen from said collecting space, means for improving the purity of the oxygen product including means for introducing oxygen in gaseous form and at a higher temperature than said relatively pure oxygen in said collecting space into said collecting space at a point therein below the top of the liquid oxygen therein and means for regulating the quantity of oxygen introduced including a control valve having servo means for governing the position thereof including surfaces one constantly subjected to the pressure of the oxygen in gaseous form and an opposed surface subjected to the pressure of said gaseous oxygen or a lower pressure and controlling means for the pressure on said last mentioned surface including a further valve governed by the temperature of the descending stream of liquid as it reaches said collecting space.

16. In combination, in a gas separation apparatus, a column containing means for providing a large cumulative surface area at which a rising current of a gas and a descending stream of liquid may interact, and having a collecting space for a liquid product of the rectification process performed within said column, means for

5 withdrawing such product from said collecting space, means for vaporizing the same and for making the same available in the gaseous state at a pressure exceeding the pressure within said column, means for conducting some of said product into said column, and means for controlling the quantity of said product conducted into said column including a valve having controlling means responsive to the temperature of the descending stream of liquid as it reaches the bottom of said first mentioned means and including a pressure responsive device having oppositely facing surfaces and means for subjecting said device on its oppositely facing surfaces to the pressure in said collecting space and to the vapor pressure, at the temperature of said descending stream of liquid at the point stated, of the product substance in a form purer than desired product purity.

10 17. In combination, in a gas separation apparatus, a column containing means for providing a large cumulative surface area at which a rising current of a gas and a descending stream of liquid may interact, and having a collecting space 15 for a liquid product of the rectification process performed within said column, means for withdrawing such product from said collecting space, means for vaporizing the same and for making the same available in the gaseous state at a pressure exceeding the pressure within said column, means for conducting some of said product into said column, and means for controlling the quantity of said product conducted into said column including a valve having controlling means responsive to the temperature of the descending stream of liquid as it reaches the bottom of said first mentioned means and including a pressure responsive device having oppositely facing surfaces and means for subjecting said device on its oppositely facing surfaces to the pressure in said collecting space and to the vapor pressure, at the temperature of said descending stream of liquid at the point stated, of the product substance in a form less pure than desired product purity.
